(57) **CLAIM**

The ornamental design for an ultrasound robot as shown and described.

DESCRIPTION

FIG. 1 is a rear view of an ultrasound robot, in a first position, showing our new design;

FIG. 2 is a bottom view thereof.

FIG. 3 is a front view thereof.

FIG. 4 is a front left perspective view thereof.

FIG. 5 is a rear right perspective view thereof.

FIG. 6 is a left view thereof.

FIG. 7 is a right view thereof.

FIG. 8 is a top view thereof.

FIG. 9 is a rear view of an ultrasound robot, in a second position, showing our new design;

FIG. 10 is a bottom view thereof.

FIG. 11 is a front view thereof.

FIG. 12 is a front left perspective view thereof.

FIG. 13 is a rear right perspective view thereof.

FIG. 14 is a left view thereof.

FIG. 15 is a right view thereof.

FIG. 16 is a top view thereof.

FIG. 17 is a rear view of an ultrasound robot, in a third position, showing our new design;

FIG. 18 is a bottom view thereof.

FIG. 19 is a front view thereof.

FIG. 20 is a front left perspective view thereof.

FIG. 21 is a rear right perspective view thereof.

FIG. 22 is a left view thereof.

FIG. 23 is a right view thereof.

FIG. 24 is a top view thereof.

FIG. 25 is a rear view of an ultrasound robot, in a fourth position, showing our new design.

FIG. 26 is a bottom view thereof.

FIG. 27 is a front view thereof.

FIG. 28 is a front left perspective view thereof.

FIG. 29 is a rear right perspective view thereof.

FIG. 30 is a left view thereof.

FIG. 31 is a right view thereof; and,

FIG. 32 is a top view thereof.
